CHARLES E. BROOKS, OF MONTREAL, QUEBEC, CANADA

LOCOMOTIVE BOILER

Application filed November 21, 1929. Serial No. 408,835.

This invention relates to certain improvements in locomotive boilers.

The invention is concerned, particularly, with boilers of the type heretofore provided with a steam dome and an inside dry pipe. In such a boiler, a certain amount of water enters the steam dry pipe, due to the surging of the boiler water and to the relatively large opening placing the steam dome in communication with the boiler steam space. The scale and other foreign matter entrained by the water entering the dry pipe is carried to the super-heater and to the engine cylinder and is the cause of much damage, such, for example, as the blowing out of cylinder heads. The internal arrangement of the dry pipe is also a disadvantage in that it constitutes an obstruction in the space between the fire tubes and the top of the boiler.

The object of the present invention is to eliminate the steam dome and inside dry pipe and to provide improved means for collecting and conveying steam from the boiler.

According to my invention, an outside dry pipe is mounted to extend longitudinally above the top of the boiler. The dry pipe is surrounded by one or more enclosed steam spaces communicating with a plurality of relatively small openings formed, preferably, in the uppermost portion of the boiler. The dry pipe is provided with a multiplicity of relatively small apertures placing the interior of said pipe in communication with the surrounding enclosed space or spaces. This arrangement is particularly adapted for front end throttle locomotives and the steam passes from the boiler through the dry pipe to the super-heater header and front end throttle box assembly. A steam shut-off valve is arranged in the external dry pipe to afford a means of cutting off the flow of steam from the boiler to permit of repairs or examinations being effected with respect to the throttle valve or super-heater header while the engine is under steam.

The external arrangement of the dry pipe practically eliminates the entrance of water particles due to the surging of the boiler water. The plurality of openings formed in the boiler for the escape of steam are located near the centre of

oscillation of the boiler water and are relatively small in area so that the steam flow is distributed over a larger extent of water surface. The total area of these openings is considerably greater than the cross sectional area of the dry pipe, but less than the area of opening heretofore provided for placing the steam dome in communication with the boiler steam space. The new arrangement, therefore, enables a considerable reduction in the section of the boiler shell cut away for its application, as compared with that required for the usual steam dome construction. The distribution of the steam outlet from the boiler among a plurality of openings of small diameter greatly reduces the tendency of the boiler water to lift and enter the dry pipe. Moisture carried into the enclosed steam space or spaces surrounding the dry pipe will be substantially separated from the steam during passage of the latter through the relatively small perforations formed in the wall of said pipe. The enclosed steam space or spaces surrounding the dry pipe serve as condensate collecting chambers from which the condensate is returned to the boiler through the aforesaid openings placing the boiler in communication with said space or spaces. The external dry pipe is of further advantage in that it leaves clear the space above the fire tubes, thereby increasing the available steam storage space of the boiler and permitting freer access to the interior of the boiler through a suitable unobstructed manhole which may be provided in the top of the boiler shell. The total area of the openings formed in the boiler, including the manhole and the steam outlet openings referred to, is less than the area of opening required in connection with the customary steam dome installation.

Proceeding now to a more detailed discussion of the invention, reference will be had to the accompanying drawings, in which

Figure 1 is a view in side elevation showing the general appearance of a locomotive equipped with my invention in place of the customary steam dome and inside dry pipe arrangement.

Figure 2 is a longitudinal sectional view

showing the construction of the external dry pipe and the manner of connecting same to the boiler and to the super-heater header.

Figure 3 is a view similar to Figure 2, but disclosing a slight modification.

Figure 4 is a fragmentary longitudinal sectional view through the upper portion of the boiler, showing the arrangement of a perforated plate serving to prevent the surging of any considerable amount of boiler water into the passages leading to the external dry pipe.

Figure 5 is a sectional view taken on the line 5—5 of Figure 4.

The preferred embodiment of the invention is illustrated in Figures 1 and 2. In these figures, 11 designates a boiler provided with a plurality of relatively small openings 12 communicating with steam passages 13 formed in the base portions 14 of a plurality of saddles 15. These saddles carry a seamless metal tube 16 provided with bottom openings 16a registering with the steam passages 13. The external dry pipe indicated at 17 passes through the tube 16 and has its rear terminal 25 attached to and suitably supported by the rearmost saddle 15. The forward end of tube 16 is swaged into engagement with pipe 17 as indicated at 18. The dry pipe is of smaller diameter than the tube 16, so that the latter 30 forms an enclosed steam space 19 surrounding the dry pipe and communicating therewith through the medium of a plurality of relatively small apertures 20 formed in the upper half of said pipe. The rearmost saddle 15 is provided with a cover 21 to permit attachment of the dry pipe to said saddle and to facilitate inspection and cleaning of the pipe. The forward end of dry pipe 17 is connected, by expansion joint 22 and valve casing 23, 40 to the super-heater header and front end throttle box assembly generally designated by reference character 24. A shut-off valve 25 of any suitable type is arranged in the valve casing 23 so that the flow of steam from the boiler may be interrupted whenever it is desired to inspect or repair the throttle valve or super-heater header while the engine is under steam. A manhole 26, provided with a suitable cover 27, is formed in the boiler adjacent the rearmost saddle 15 so as to afford 50 access to the clear space provided in the boiler above the fire tubes. Ample facilities for inspection and cleaning are provided by openings 28 formed in the saddles 15 and in the valve casing 23, it being understood that these openings are normally closed by suitable plugs.

In the arrangement above described, the steam passes from the boiler into the enclosed steam space 19 provided between the tube 16 and the dry pipe 17. From this space the steam passes into the interior of the dry pipe through the apertures 20. As these apertures 20 are formed only in the upper half of the steam pipe, the lower half of the

pipe serves to baffle the flow of the steam and to provide a condensate collecting surface, from which the condensate drops to the bottom portion of the tube 16 and returns to the boiler through the passages 13. A further separation of moisture from the steam is effected, as the steam passes through the relatively small openings 20 into the interior of the dry pipe and this moisture accumulating around the edges of the apertures 20 finds its way to the bottom of the tube 16 and is also returned to the boiler through the passages 13. Any condensate accumulating within the dry pipe 17 is permitted to escape therefrom through the openings 29 formed in the lower portion of said pipe.

The dry pipe 17 is eccentrically arranged within the tube 16 so that a somewhat greater clearance is secured between the lower portions of the pipe and tube to provide a condensate collecting chamber of considerable volume.

In order to further baffle the tendency of the boiler water to surge into the passages leading to the external dry pipe, I may provide a perforated plate 31 having its body portion spaced from the top of the boiler shell directly below the openings and passages placing the boiler in communication with the external dry pipe. The side edges of plate 31 are flanged downwardly as at 32 and bolted or otherwise secured to angles 33 which are fastened to the upper portion of the boiler shell. The ends of the plate 31 are turned upwardly into engagement with the boiler shell, as indicated at 34.

In the modification disclosed in Figure 3, the external dry pipe comprises a rear section 17a and a front section 17b. The rear section 17a is of greater diameter than the front section and is mounted directly in the saddles 15a. These saddles are provided with internal channels 15b affording enclosed steam spaces surrounding the pipe section 17a and communicating with the boiler through openings 12a and 13a, corresponding to the openings 12 and 13 described in connection with Figure 2. The enclosed steam spaces 15b communicate with pipe section 17a through the medium of relatively small openings 20a formed in the portions of the pipe section surrounded by said enclosed spaces. The rear end of pipe section 17b is received in the front end of pipe section 17a, the latter being reduced in diameter by a swaging indicated at 17c. The manner of connecting the two pipe sections is such that the bottom of the pipe section 17b is in a higher plane than the bottom of the pipe section 17a, so that the lower portion of the section 17a serves as a sump or condensate collecting chamber of considerable volume, the condensate accumulating therein being returned to the boiler through the openings 20a and passages 13a. The forward end of the pipe 130

section 17b is connected to the super-heater header and front end throttle assembly 24, as described in connection with Figure 2.

In the form of invention shown in Figure 3, the apertures 20a provided in the pipe section 17a are spaced around the entire circumference of said pipe section, but the size of these apertures is relatively small so that as the steam passes therethrough the moisture particles contained in the steam will accumulate around the edges of the apertures and will be returned as condensate to the boiler. Condensate precipitated within the pipe sections 17a and 17b finds its way back to the boiler through the apertures 20a when the throttle is eased down.

As shown to advantage in Figure 1, the external dry pipe assembly is enclosed by a suitable jacket 36 bolted or otherwise fastened to the top of the boiler shell. It will also be understood that the dry pipe assembly will, in actual practice, be completely covered by substantial lagging.

Having thus fully described my invention, it will be understood that various changes in the construction and arrangement of parts may be resorted to within the scope of the appended claims.

Having thus described my invention, what I claim is:

1. A locomotive boiler having a plurality of openings in the top wall thereof, a plurality of saddles mounted on the boiler and provided with bottom openings communicating with said boiler openings, said saddles also having openings extending therethrough in the longitudinal direction of the boiler, an external dry pipe supported to extend through the last mentioned openings of the saddles and one or more enclosed steam spaces surrounding said pipe and communicating with the bottom openings of the saddles, said dry pipe being provided with openings placing the interior of the pipe in communication with said enclosed steam space or spaces.

2. A locomotive boiler equipped with an external dry pipe replacing the customary steam dome and inside dry pipe installation, a tube surrounding a portion of the dry pipe and spaced therefrom to provide an intervening steam space, one end of said tube being directed inwardly into engagement with the dry pipe to close the corresponding end of the steam space, a plurality of saddles having base portions secured to the top of the boiler and apertured body portions surrounding and supporting said tube, one of said saddles being formed to close the remaining end of said steam space and the base portions of said saddles being provided with steam passages placing the interior of the boiler in communication with the enclosed steam space between the dry pipe and tube, said dry pipe having apertures placing the

interior of the pipe in communication with said enclosed space.

3. A locomotive boiler equipped with an external dry pipe replacing the customary steam dome and inside dry pipe installation, supporting saddles surrounding the dry pipe and mounted on the top of the boiler, said saddles being recessed to provide enclosed steam spaces around the dry pipe, and steam passages placing said enclosed steam spaces in communication with the boiler and with the interior of the dry pipe.

In witness whereof, I have hereunto set my hand.

CHARLES E. BROOKS.
